UNITED STATES PATENT OFFICE.

BRUNO BEUCHEL, OF KALAMAZOO, MICHIGAN, ASSIGNOR TO HIMSELF AND
W. ROEDIGER, OF SAME PLACE.

IMPROVEMENT IN HOISTING-JACKS.

Specification forming part of Letters Patent No. 96,299, dated November 2, 1869.

To all whom it may concern:

Be it known that I, BRUNO BEUCHEL, of Kalamazoo, in the county of Kalamazoo and State of Michigan, have invented certain Improvements in Hoisting-Jacks, of which the following is a specification.

The object of my invention is to increase the power of the hoisting-jack by means of back gears and a screw; also, to change the motion by shifting the handle from one crank-shaft to the other, thus increasing the lifting-power or the motion of machine, as required. It may be used in lifting fence-posts or any other object near the surface of the ground; also, to lift buildings, cars, or any other object beneath which it can be placed.

In the accompanying drawings, Figure 1 is a perspective view of a machine embodying my invention. Fig. 2 is a view of the lifting-bar. Fig. 3 is a view of the case of the hoisting-jack. Fig. 4 is a view of the screw, gears, shafts, and handle.

A is the case, which should be made of cast-iron, with the movable caps B and C at each end, so that the lifting-bar, screw, and gears may be readily removed for repairs.

D is a projection in the middle of the case, by means of which it rests on a frame-work when used as a stump-puller, as seen at Fig. 1. The lifting-bar, Fig. 2, is furnished with

cogs on one side, into which the screw meshes, and by means of which it is raised and lowered; or it may be made as a screw and placed inside of screw G, the latter being used as a nut.

E is a projection from the base of the lifting-bar, to which may be attached any object to be lifted from the ground.

F is a cap, to be placed firmly under any object which is to be raised.

G, Fig. 4, is the screw, held in position by the plates H and I. To its base is attached a bevel-wheel, J, which meshes into the pinion K. The pinion K is attached to the spur-wheel L, and spur-wheel L meshes into spur-pinion M, which is connected with the handle by shaft N.

O is a latch, which, by dropping into the cogs of pinion M, prevents the lifting-bar being pressed downward by the weight which is being raised. The handle being placed on crank-shaft P, increases the motion.

I claim as my invention—

The combination of screw G, lifting-bar, Fig. 2, gears J K L M, and latch O, in the manner and for the purpose set forth.

BRUNO BEUCHEL.
